UNITED STATES PATENT OFFICE.

ADOLF BANGERTER, OF NEW BRIGHTON, NEW YORK.

MECHANICAL TOY.

Application filed January 5, 1924. Serial No. 684,664.

Among the principal objects which the present invention has in view are: to provide a mechanism resembling in part an animate figure; to visibly perform the operation of tracing or drawing a picture; to provide means for indicating the completion of the functioning cycle; to provide operating means for manipulating a plurality of said toys separately and in competition; and to provide skill-provoking means for driving the mechanisms.

Drawings.

Figure 1 is a longitudinal section showing schematically the arrangement of a toy and operating means therefor constructed and arranged in accordance with the present invention.

Figure 2 is a longitudinal section of the display platform on which toys are mounted together with an electric wiring layout for operating the indices announcing the completion of a contest employing a number of said toys, the section being taken on the line 2—2 in Fig. 1.

Figure 3 is a plan view partly in section on line 3—3 showing the manipulative hand-operating mechanism with which each toy is provided.

Figure 4 is a vertical section on enlarged scale of the operating mechanism connected with the marking device, the section being taken on the line 4—4 in Fig. 1.

Figure 5 is a vertical section, the section being taken on the line 5—5 in Figure 11.

Figure 6 is a detailed view on enlarged scale and in section showing the magazine for holding cards to be drawn upon on each of the various toys, the section being taken as on the line 6—6 in Fig. 4.

Figure 7 is a cross section of a feeding mechanism for the magazine, the section being taken on enlarged scale and taken as on the line 7—7 in Fig. 6.

Figure 8 is a detailed view of an articulated mechanism for supporting and guiding the marking member.

Figure 9 is a sectional view thereof, the section being taken on the line 9—9 in Fig. 8.

Figure 10 is an enlarged section of one of the joints, the section being taken as on the line 10—10 in Fig. 8.

Figure 11 is a rear elevation of the operating mechanism, the reverse of what is shown in Figure 4 of the drawings.

Figure 12 is a detailed view on enlarged

scale partly in section showing a fragment of the electric switches with which the announcing mechanism is provided, the section being taken on the line 12—12 in Fig. 13.

Figure 13 is a detailed view on enlarged scale of the stopping mechanism with which the toys are each provided.

Description.

As seen best in Figure 1 of the drawings, each toy has a visible marking member 20. The member 20 is operatively connected with a mechanism contained in the casing 21.

Simulation of a connection between the element 20, which simulates the human hand and the body 22 of a doll, is effected by covering the wrist portion of the member 20 with the sleeve 23 of a gown or fabric covering 24 which is draped on the body 22 and over the frame 25 upon which the body 22 is mounted. First, the frame 25 is removably secured to the casing 21 by means of screws 26 or other suitable devices. It will be understood that no movement is imparted to any portion of the visible doll figure other than to the hand or element 20.

As indicated best in Figure 2 of the drawings, a series of casings 21 are preferably employed, the mechanism in each of said casings 21 being operatively connected by belts 27 with pulleys provided on spools 28 loosely mounted on the motor-driven shaft 29. The spools 28 are each operatively connected with the shaft 29 by clutch members 30, which normally engage teeth provided on the spools 28 by means of the springs 31.

It will be understood that the shaft 29 is rotated by an electric motor 32 only when it is desired to reset the mechanism, at the completion of any operation as hereinafter set forth. To this end the motor 32 is connected to a driving pulley 33 by means of a belt 34, as can be seen best in Figures 1 and 2 of the drawings.

Normally, the mechanisms controlling the marking members 20 in the various casings 21 are driven by a hand wheel 35, the periphery whereof is adapted to frictionally engage a tire on the transmission wheels 36. Each transmission wheel 36 is independently mounted on a shaft 37, and has a pulley 38 which is operatively engaged by means of a belt 39 with a pulley 40 on a shaft mounted in a separate standard 41. A second pulley 42 is rigidly connected with the pulley 40 and is operatively connected

with one of the spools 28 by an independent belt 43. By means of this arrangement it is obvious that each of the mechanisms contained in each casing 21 is operated independently by the person manipulating the hand wheel 35.

The manipulation of the hand wheel 35 is dependent on skill and care due to the fact that said wheel is turned by means of a crank handle 44 and is pivoted on a shaft 45 by a pivoted bracket 46 which is hinged to the standards 47 by the hinge pin 48.

The free end of each bracket 46 is supported by means of a cushion spring 49, the normal operation of which is to lift the wheel 35 from engagement with the wheel 36. The arrangement between the two wheels is effected only by the operator pressing the wheel 35 downward against the expansion of the spring 49. As part of the travel of his hand when grasping the crank 44 is upward, it is obvious that the amount of duration of contact between the wheels 35 and 36 will vary with the skill and knowledge of the various persons operating the said wheels. The result of the operation would be that the person causing the marking element 20 to complete the picture such as shown in Figure 4 of the drawings first, will be considered the winner of the prize or merit or reward of merit in the particular contest.

With the completion of each picture by any particular toy having the marking element 20, the electric lamp 50 associated with the magazine 51 with which the particular toy is provided, is caused to glow due to the fact that the switch element 52 in the particular casing has been moved to contact with the stationary switch element 53 which completes the circuit in which the particular lamp is incorporated.

As will be hereafter described, the mechanism which first completes its cycle, will complete the electric circuit incorporating the lamp 50 associated with it and render it impossible to complete the electric circuits in all of the other mechanisms associated in the game or contest.

As seen best in Figure 11 of the drawings, rocking shaft 55 extends through and between all of the casings 21 and has rigidly mounted thereon within each casing an arm 57. Each arm 57 has a pin 68 normally resting in the slot 58 of a link 59. The arm 57 has at the upper end thereof a wedge-shaped end 60, the office of which is to extend behind and displace outward the plunger 61 on each of the elements 52.

As previously explained, each of the elements 52 are moved to contact with the element 53 of each circuit incorporating one of the lamps 50.

Normally, each of the ends 60 rests in the

path of the cam 62 to ride over the inclined surface thereof. The sharp edge of the wedge end 60 is thus introduced behind the plunger 61 to press the same outward against the switch element 52 to move the same to engage with the switch element 53 with which it is associated.

As previously explained, the completion of the circuit between the elements 52 and 53 operates to light the lamp 50 associated with some one of the dolls.

The arm 57 is so mounted, that when pressed outward by the cam block 62, it rocks the shaft 55, and the arms 57 are rocked outward so that the ends 60 of the various arms 57 pass outside of the block 62 and between the head of the plunger 61 and inside of the switch element 52. Horizontal rods, 63, are attached to the arms 57, and extend loosely through holes in the casings. These rods serve merely as guide members to insure accurate functioning of the arms, 57.

In this manner provision is made for avoiding the later completion of electric circuits having the lamps 50 associated with other toys.

From the foregoing it is obvious that at the completion of the game, the lamp associated with the toy which has completed the picture first, will show and that lamp only, though the other toys may be manipulated to the point of completion of their respective pictures.

At the completion of the picture in each mechanism, a clutch 64 on the driving shaft 65 is thrown. To this end a rocker arm 66 is pivotally connected with the link 59 by a ball and socket joint indicated by the numeral 67 in Figures 4 and 11 of the drawings.

The link 59 is suspended between the ball and socket joint 67 and a pin 68 laterally extended from the arm 57. As seen best in Figure 13 of the drawings, the elongated slot 58 in the link 59 permits the movement of the link 59 laterally without changing the position of the arm 57. Set out from the link 59 is a lug 69 which normally rests in the path of a pin 70 on the face of a cam disk 71. The cam 71 is the disk which rocks the marking member 20 toward and away from the cards A in the magazine 51. These two actions, i. e., the movement of the element 21 toward the cards A and the movement retracting the element from the card A are coeval with the initiation and completion of the drawing. The pin 70 is so disposed on the cam disk 71 that it engages the lug 69 in passing and presses the said lug and the link 59 connected therewith forward to rock the rocker arm 66 to throw the clutch 64 on the shaft 65. Having thrown the clutch, the mechanism is arrested until released manually.

The movement of the member 20 is controlled during the operation of the mechanism by three cam disks 71, 72 and 73. These disks are non-rotatively mounted on a 5 shaft 74 which is provided with suitable bearings in a skeleton frame held within the casing 21. The shaft 74 is likewise provided with a worm gear wheel 75, the rotation of which is imparted to it by the worm 76 on the shaft 65. The shaft 65 as previously explained is driven by means of the belt 27 whenever the clutch 64 is engaged and belts 27 are operatively connected with the manipulating wheels 35.

15 A series of drop arms 78, 79 and 80 are hinged on the small pivot shaft 81, as seen best in Figure 11 of the drawings. The free ends of the drop arms have rollers that ride on the cams formed on the edge of the disks 20 71, 72 and 73. The arms are pivotally connected by rods 82, 83 and 84 to the levers 85, 86 and 87, respectively. The levers 86 and 87 cooperate to move the marking member 20 vertically and horizontally synchronously to cause the marking end of the pencil B to trace the lines indicated by the letter C on the card A. The lever 86 is of the bell crank type. The lever 87 is of the rocking type. The lever 86 is operatively connected with a rocking arm 88 by a link rod 89. The rod 88 is rigidly connected with or integrally formed on the marking member 20. The lever 87 is pivotally connected with the arm 88 by means of a screw pin 90. 30 For the operation of the arm 88, the levers 86 and 87 may be set to operate in the same or parallel planes while the lever 85 as best shown in Figures 8 and 9 of the drawings operates at planes perpendicular to the planes 40 of the other mentioned levers.

As seen best in Fig. 8 of the drawings, the lever 85 has a block 91 upon which is pivotally mounted the lever 87. To pivot the lever 87 a screw pin 92 is provided. From 45 this construction, it is obvious that as the block 91 is rocked, the angle of the member 20 relative to the mechanism 51 and contents thereof is changed, while the lever 87 is rocked or disposed in position to move the 50 said member 20 in all of its positions.

To permit the relatively circular movement of the block 91 and the lever 87, the rod 84 is connected with the lever 87 by means of a loose bolt connection 93. The 55 bolt 93 is held in a tubular end 94 of the lever 87 by a lock pin 95 which fits a groove 96 in the connection 93 when driven through perforations provided in the end 94, said 60 perforations being tangential to the groove 96. From this construction it is obvious that the lever 87 and the extension 94 thereof may be rotated or revolved on their axis without jamming or rocking the bolt 93 in its socket connection.

65 The cam disks are plotted with reference

to the movement of the point of the pencil B held by the hand member 20. A series of springs suitably and conveniently disposed operate to hold the rollers at the ends of the drop arms 78 to 80 inclusive firmly upon the 70 periphery of the disks 71 to 73 inclusive, therefore as said disks rotate under the said drop arms, motions are transmitted to the member 20 through the intermediate connections between the arm 88 thereof and the 75 various cams corresponding with the movement desired to be imparted to the point of the pencil B.

As above set forth the mechanism is started by the drop arm 78, first, falling to the 80 lower level on the disk 71 which imparts a movement to the block 91 that shifts the lever 87 to move the member 20 so that the point of the pencil B rests on the cardboard A in the magazine 51. In this position the 85 arm 78 and parts associated therewith remain until the roller supporting the said arm 78 is reached by the opposite end of the long dwell on the disk 71. The rise on the disk 71 then lifts the arm 78 with the result that the 90 block 91 is rocked to carry the member 20 away from the magazine 51. At that time it will be found that the point of the pencil B has returned to the spot where it first 95 touched the card A in the magazine 51.

The magazine 51 as shown best in Figures 6 and 7 has a follower-back 97. As seen in Fig. 7 of the drawings, the back 97 has an undercut bottom opening bracket 98 adapted to receive the threated end of a screw bolt 99. 100 The bolt 99 is screw-threaded to force the cards A against the forward side of the frame of the magazine 51 to hold the said cards firmly; while the point of the pencil B is being pressed thereagainst.

Each of the clutches 64 having been thrown, the operation of the rocker arm 66, thereafter operates to arrest the mechanism incorporating the disk 71 and the pin 70 thereon which is engaged with the lug 69. 110 Though the clutch is thrown, the lug 69 operates to arrest the mechanism in the position where the picture has been completed. Subsequently, all of the mechanisms are manipulated in the same way until each and all are 115 arrested through the engagement of the pins 70 and the lug 69 in each mechanism.

It will be noted by reference to Fig. 2 of the drawings that the shaft 55 on which the arms 57 are mounted has at the exposed end 120 thereof a handle 100. When the handle 100 is drawn over, the various arms 57 and parts connected therewith are rocked out of the path of the pins 70 on the disk 71. If now the motor 32 be started all of the mechanisms may be operated to bring the disks 71, 125 72 and 73 into position to inaugurate the drawing game.

While I have herein shown and described a series of cam disks shaped to produce the 130

figure shown in the drawing, it will be understood that other disks having different shapes may be substituted for the present disks to effect the representation of other figures.

It is also obvious that while I have described the disks as separable, this may be varied by forming a single block having a series of juxtaposed parallel cam edge surfaces. I consider these various modifications of the construction as comprised within the present disclosure.

Claims.

- 15 1. A toy as characterized comprising a
movable marking member; a stationary
chart magazine for disposing successive
charts adjacent to said marking member;
and power driven means for moving said
marking member successively to place a
marking point against the outermost chart
and to simultaneously move said point under
pressure over said chart, in a predetermined
path, and then to move said marking member
out of contact with said chart.

20 2. A toy as characterized comprising a
movable marking member; a stationary
chart magazine for disposing successive
charts adjacent to said marking member;
and power driven means for moving said
marking member successively to place a
marking point against the outermost chart
and to simultaneously move said point under
pressure over said chart, in a predetermined
path, and then to move said marking member
out of contact with said chart, said means
embodying a plurality of disks operatively
connected each with said marking member,
each disk having characteristic construction
30 to produce the desired movement in said
marking member.

35 3. A toy as characterized comprising a
movable marking member; a stationary
chart magazine for disposing successive
charts adjacent to said marking member;
and power driven means for moving said
marking member successively to place a
marking point against the outermost chart
and to simultaneously move said point under
pressure over said chart, in a predetermined
path, and then to move said marking member
out of contact with said chart, said means
embodying a plurality of disks operatively
connected each with said marking member,
each disk having a series of edge
40 cams, and means operatively connected with
said cams for transmitting to said marking
member, a movement corresponding with
said cams.

45 4. A toy as characterized comprising a
movable marking member; a stationary
chart magazine for disposing successive
charts adjacent to said marking member;
and power driven means for moving said
marking member successively to place a
marking point against the outermost chart
and to simultaneously move said point under
pressure over said chart, in a predetermined
path, and then to move said marking member
out of contact with said chart, said means
embodying a plurality of disks operatively
connected each with said marking member,
each disk having a series of edge
50 cams, and means operatively connected with
said cams for transmitting to said marking
member, a movement corresponding with
said cams.

55 5. A toy as characterized comprising a
movable marking member; a stationary
chart magazine for disposing successive
charts adjacent to said marking member;
and power driven means for moving said
marking member successively to place a
marking point against the outermost chart
and to simultaneously move said point under
pressure over said chart, in a predetermined
path, and then to move said marking member
out of contact with said chart, said means
embodying a plurality of disks operatively
connected each with said marking member,
each disk having a series of edge
60 cams, and means operatively connected with
said cams for transmitting to said marking
member, a movement corresponding with
said cams.

65 6. A toy as characterized comprising a
movable marking member; a stationary
chart magazine for disposing successive
charts adjacent to said marking member;
and power driven means for moving said
marking member successively to place a

marking point against the outermost chart and to simultaneously move said point under pressure over said chart, in a predetermined path, and then to move said marking member out of contact with said chart, said means embodying a plurality of disks operatively connected each with said marking member, each disk having a series of edge cams, and means operatively connected with said cams for transmitting to said marking member, a movement corresponding with said cams, and a driving mechanism for simultaneously moving said disks one complete revolution thereof. 70 75

5. A toy as characterized comprising a 80
movable marking member; a stationary
chart magazine for disposing successive
charts adjacent to said marking member,
and power driven means for moving said
marking member successively to place a 85
marking point against the outermost chart
and to simultaneously move said point under
pressure over said chart, in a predetermined
path, and then to move said marking member 90
out of contact with said chart, said
means embodying a plurality of disks opera-
tively connected each with said marking
member, each disk having a series of edge
cams, and means operatively connected with
said cams for transmitting to said marking 95
member, a movement corresponding with
said cams, and a driving mechanism for
simultaneously moving said disks one com-
plete revolution thereof; and means for
automatically arresting the movement of 100
said disks.

6. A toy as characterized comprising a plurality of marking members and mechanisms operatively connected with said members for imparting thereto, simultaneously, a variety of movements; a plurality of means for operating each of said marking members, said means being spaced apart from said marking members and mechanisms connected therewith; said means being adapted for frictionally engaging said mechanisms for irregular intervals; and means operatively connected with the operating means for each of said marking members for arresting the movement of said marking members at the completion of their function.

7. A toy as characterized comprising a plurality of marking members and mechanisms operatively connected with said members for imparting thereto, simultaneously, a variety of movements; a plurality of means for operating each of said marking members, said means being spaced apart from said marking members and mechanisms connected therewith, said means being adapted for frictionally engaging said mechanisms for irregular intervals; means operatively connected with the operating means for each of said marking members for arresting the movement of said marking members at the 130

completion of their function; and means operatively connected with each of said marking members for displaying visibly a device for indicating the completion of its

5 function.

8. A toy as characterized comprising a plurality of marking members and mechanisms operatively connected with said members for imparting thereto, simultaneously, 10 a variety of movements; a plurality of means for operating each of said marking members, said means being spaced apart from said marking members and mechanisms connected therewith, said means being adapted for

frictionally engaging said mechanisms for 15 irregular intervals; means operatively connected with the operating means for each of said marking members for arresting the movement of said marking members at the completion of their function; and means 20 operatively connected with each of said marking members for displaying visibly a device for indicating the completion of its function; and means for preventing the operation of other devices, simultaneously, 25 with the suspension of the operation of the first mentioned device.

ADOLF BANGERTER.
